PRESSURE FEEDING ATTACHMENT FOR
TAPPING MACHINES

Gerald E. Smith, Lower Salem, Ohio

Application July 7, 1942, Serial No. 450,073

7 Claims. (Cl. 10—129)

The present invention relates to tapping machines and has for its primary object to provide a compressed air feed attachment for controlling the feeding of the tap under uniform pressure and feed in relation to the work whereby to eliminate the objectionable features in a machine of this character employing manual pressure for applying the tap during the operation of the machine.

A further object of the invention is to provide an attachment of this character of simple and practical construction, which is efficient and reliable in performance, relatively inexpensive to manufacture and install in operative position upon a conventional form of tap machine, and which is otherwise well adapted for the purposes for which the same is intended.

Other objects and advantages reside in the details of construction as more fully hereinafter described and claimed, reference being had to the accompanying drawings forming part hereof, wherein like numerals refer to like parts throughout, and in which:

Figure 1 is a side elevational view.

Figure 2 is a front elevational view.

Figure 3 is a vertical sectional view through the air cylinder.

Figure 4 is a sectional view through the foot pedal control valve.

Figure 5 is a side elevational view showing the opposite side from that shown in Figure 1.

Figure 6 is a fragmentary top plan view, and

Figure 7 is a sectional view taken substantially on a line 7—7 of Figure 5.

Referring now to the drawings in detail, wherein for the purpose of illustration I have disclosed a preferred embodiment of the invention, the numeral 5 designates the base of a conventional form of drill press from which rises a tubular standard 6 on which is mounted a bracket 7 which carries a motor 8 at one side while in the other side is suitably journaled a shaft 9, the shaft being driven by means of a stepped pulley 10 operatively connected to the shaft, while a stepped pulley 11 is keyed to the motor shaft, the pulleys being operatively connected by means of a belt 12.

The shaft 9 carries a tapping attachment 13 secured in a chuck 14 for holding a tap 15. A table 16 is adjustably carried upon the standard and is adapted to hold the work to be tapped in a manner well known in the art.

The shaft 9 includes spaced flanges 17 and 18 between which a yoke 19 is positioned, the yoke being pivoted as at 20 on the bracket 7, and the

other end of the yoke is connected to the upper end of a vertically disposed rod 21, the lower end of the rod being slidably mounted in the upper end of a tube 22 which is pivotally attached at its lower end to a foot treadle 23 by means of the pin 24. A collar 25 carried by the tube 22 is adjustably secured to the rod 21 by a set screw 25' to actuate the yoke 19 for lowering the tap into work-engaging position. A spring 23' attached to the treadle returns the tap to its normal position. The foregoing operating mechanism for the tap is of conventional construction and is employed when foot pressure is desired for operating the tap into its work-engaging position.

A bracket 26 is attached to the standard 6 by means of U-bolts 27, the bracket supporting a cylinder 28 thereon in an upright position, the cylinder having a piston 29 working therein and to which a piston rod 30 is attached by means of a wrist pin 31. The rod 30 is of tubular construction and extends upwardly in substantially spaced parallelism with respect to the tube 22 and slidably positioned in the upper end of the piston rod 30 is a rod 32 which acts as a guide for the piston rod, the upper end of the rod 32 being attached to the bracket 7 by means of a brace structure 33. The upper end of the piston rod 30 is connected to the rod 21 by means of a split clamp 34 secured to the piston rod, the clamp having a forked end 35 engaged under a collar 36 adjustably secured to the rod 21 by means of a set screw 37. Accordingly, an upward movement of the piston 29 and rod 30 will cause a similar movement to the rod 21 whereby to lower the tap.

An air feed pipe 38 extends upwardly through the bracket 26 into the lower end of the cylinder 28, the air feed pipe having a rotary valve 39 therein which includes a casing 40 having a discharge port 41, the pipe 38 communicating with the casing equidistantly between the discharge port 41 and an air intake port 42. The valve 39 is formed with radially extending passages 43 and 44 communicating at their inner ends and adapted to connect the pipe 38 with the port 42 when the valve is in one position and adapted to connect the pipe 38 with the port 41 when the valve is in another position. A compressed air supply pipe 45 is connected to the port 42 leading to a suitable source of compressed air supply and the pipe 45 has a valve 46 therein together with a pressure regulator 47 of conventional construction so that a uniform pressure may be admitted to the cylinder 28, when desired.

A shaft 48 is provided for the valve 39 and projects outwardly through one side of the casing 40 and to which is secured a foot pedal 49 by means of a U-bolt 50.

Accordingly, upon a rocking movement of the pedal 49 by the foot of the operator, the valve 39 will be moved into its opened and closed positions for admitting air under pressure to the cylinder 28 or exhausting the air therefrom, when desired.

An adjustable relief valve 51 is connected to the discharge port 41 to control escape of air from the cylinder in order to synchronize the movement of the piston with the backing out of the tap from the work so as to prevent mutilation of the threads by too great a lifting force on the tap.

It is believed the details of construction, operation and advantages of the device will be readily understood from the foregoing without further detailed explanation.

Having thus described the invention what I claim is:

1. In a tapping machine having a manually operated rod for moving the tap into and out of engagement with the work, a fluid pressure actuated rod, and means operatively connecting the second-named rod to the first-named rod for actuating the tap by either of said rods, one of said rods remaining inactive upon actuation of the other rod.

2. In a tapping machine, a rod operatively connected to the tap for moving the latter into and out of engagement with the work, a second rod, means operatively connecting the said rods for actuating the first-named rod in a direction to cause engagement of the tap with the work, fluid pressure operating means for the second rod, said first-named rod being manually operable independently of the second rod and spring means for moving the tap out of work-engaging position.

3. In a tapping machine, a rod operatively connected to the tap for moving the latter into and out of engagement with the work, a cylinder, a piston working therein, a rod connected to the piston, means for subjecting the piston to fluid pressure, means connecting the rods for actuation of the tap into work-engaging position upon a movement of the second-named rod in one direction, said first-named rod being manually operable independently of the second rod, and spring means for moving the tap out of work-engaging position.

4. In a tapping machine, a rod operatively

connected to the tap for moving the latter into and out of engagement with the work, a cylinder, a piston working therein, a tubular rod connected to the piston and disposed in parallel relation to the first-named rod, a guide rod for the tubular rod, means connecting the first and second rods for simultaneous actuation upon a movement of the tubular rod in one direction, said first-named rod being free for independent movement, and means for subjecting the piston to fluid pressure.

5. In a tapping machine, a rod operatively connected to the tap for moving the latter into and out of engagement with the work, a cylinder, a piston working therein, a tubular rod connected to the piston and disposed in parallel relation to the first-named rod, a guide rod for the tubular rod, means connecting the first and second rods for simultaneous actuation upon a movement of the tubular rod in one direction, said first-named rod being free for independent movement, a fluid pressure supply pipe connected to the cylinder, a control valve in said pipe, and a foot pedal for said valve.

6. In a tapping machine, a rod operatively connected to the tap for moving the latter into and out of engagement with the work, a cylinder, a piston working therein, a rod connected to the piston, means for subjecting the piston to fluid pressure, means connecting the rods for actuation of the tap into work-engaging position, spring means for moving the tap out of work-engaging position, said first-named rod being free for independent movement, and an adjustable relief valve for the cylinder to regulate exhaust of fluid pressure therefrom in accordance with the withdrawing movement of the tap.

7. In a tapping machine, a rod operatively connected to the tap for moving the latter into and out of engagement with the work, a cylinder, a piston working therein, a tubular rod connected to the piston and disposed in parallel relation to the first-named rod, a guide rod for the tubular rod, means connecting the first and second rods for simultaneous actuation upon a movement of the tubular rod in one direction, said first-named rod being free for independent movement, a fluid pressure supply pipe connected to the cylinder, a rotary control valve in said pipe, and a rockable foot pedal connected to said valve and arranged for opening and closing the valve upon opposite rocking movement of the pedal.

GERALD E. SMITH.
